CLAIM

The ornamental design for sunglasses, as shown and described.

DESCRIPTION

FIG. 1 is a front elevational view of sunglasses showing my new design;

FIG. 2 is a rear elevational view thereof;

FIG. 3 is a right-hand side view thereof, the left-hand side view thereof being a mirror image of the side shown;

FIG. 4 is a top plan view thereof;

FIG. 5 is a bottom view thereof;

FIG. 6 is a perspective view thereof; and,

FIG. 7 is a reference perspective view thereof in a state where ear pieces are removed from the ear stems of the sunglasses.
